CARD INDEX SYSTEM

Harry A. Wardy, Los Angeles, Calif., assignor to
Add-A-Guide, Incorporated, Los Angeles,
Calif., a corporation of California.

Application June 7, 1937, Serial No. 146,884

14 Claims. (Cl. 129—16.1)

This invention relates to filing devices for papers, cards, etc. and relates more particularly to devices of the type generally known as card index systems. A general object of this invention is to provide a card index system that is simple, practical and inexpensive, and that is very effective and convenient to use.

Another object of this invention is to provide a card index system or device in which the cards are normally arranged in compact groups or packs to occupy a minimum of space and are arranged in such a manner that the identifying tabs of all of the cards of any pack or of all the packs may be immediately made plainly visible by simple, rapid manual operations.

Another object of this invention is to provide a card index device or system of the character mentioned in which the cards may remain in the extended or raised positions where their tabs are plainly visible until deliberately dropped or moved to their normal positions, the cards being freely accessible for removal, inspection, sorting, etc. when in said position and being free so that they may be removed and dropped individually or collectively to assume positions where they are properly located and related to be raised for a subsequent use.

Another object of this invention is to provide a card index device or system of the character mentioned in which all of the cards of a pack are simultaneously brought to positions where their identifying tabs are plainly visible by merely raising a lifting element that may bear identification means or classifying means identifying the group or pack of cards thus raised.

An important object of this invention is to provide a card index system of the character mentioned in which any one or all of the cards of any pack may be removed from the file box or drawer and restored to their original positions at any time without special manipulation and without the handling or manipulating of any mechanical parts. The filing device of the present invention is such that the papers or cards may be directly and easily removed from the file drawer or box individually or in groups, when the cards are in their normal, compact relation or in the fanned out or raised positions where their tabs are visible and may be easily restored or returned to their original positions, the cards remaining in the raised positions until deliberately dropped and those that are dropped returning to their correct original positions. This feature of the device permits the withdrawal of the cards at will, allows postings or entries to be conveniently made on the

cards by hand, by typewriter, or the like, and allows the replacement of worn cards, the removal of obsolete cards, and the easy insertion of new or additional cards. In most of the so-called visible card indexes heretofore introduced the cards were mechanically locked in the boxes or files or locked in hinged folders or locked to one another in such a manner that they could not be removed without the manipulation of mechanical parts or without detachment from one another, with the result that new entries on the cards had to be made in longhand and usually with the writer in a difficult or uncomfortable position.

Another object of this invention is to provide a card index device or system of the character mentioned in which the several cards of each unit or pack may be made easily accessible with their tabs plainly visible whereby the cards of each pack may be quickly sorted and handled with a minimum of thumbing and following the necessary sorting, reference, or other operations, the packs may be easily collapsed or returned to their original compact condition with the cards in their proper sequence.

Another object of this invention is to provide a card index device or system in which a mis-filed or incorrectly positioned card is immediately projected to a position above the adjacent cards or is dropped to a position below the adjacent cards when the pack of cards is expanded or fanned out for use, whereby the incorrect position of such a card is immediately made evident.

A further object of this invention is to provide a card index system or device of the character mentioned that is suitable for use in drawers, boxes and files of various characters and in trays and boxes of conventional filing systems which have been slightly altered, and that embodies simple, inexpensive holder units and card packs that may be removed from or added to the system as occasion arises.

The various objects and features of my invention will be fully understood from the following detailed description of a typical preferred form and application of the invention, throughout which description reference is made to the accompanying drawings, in which:

Fig. 1 is a front elevation of a card index system of the present invention showing the cards of the foremost holder of the system in their elevated positions. Fig. 2 is a reduced side elevation of the box of the system or device with the ends in the open positions. Fig. 3 is a fragmentary vertical detailed sectional view taken as indicated

by line 3—3 on Fig. 1 showing some of the cards of the second to the foremost holder in their elevated positions. Fig. 4 is an enlarged side elevation of one of the holders removed from the box with the cards removed and the lifting element in its raised position. Fig. 5 is a reduced vertical detailed sectional view taken as indicated by line 5—5 on Fig. 4. Figs. 5^a and 6 are enlarged vertical fragmentary detailed sectional views taken as indicated by lines 5^a—5^a and 6—6, respectively, on Fig. 5. Figs. 7 and 8 are enlarged fragmentary horizontal detailed sectional views taken as indicated by lines 7—7 and 8—8, respectively on Fig. 5 and Fig. 9 is a front elevation of a pack of cards removed from its holder.

The features of the present invention may be embodied in card systems and loose leaf systems for various purposes and the devices of the invention may be embodied in drawers, boxes, files, etc., of different types, sizes and characters. In the following detailed description I will describe a typical embodiment of the invention for use in a more or less conventional drawer or box, it being understood that the invention is not to be construed as limited or restricted to the specific form or application about to be described.

The card index system or device of the present invention includes, generally, a suitable container or box 10, a multiplicity of holders 11 removably retained in the box 10, a group or pack of cards C in each holder 11 free to be removed and replaced at will, and means 12 associated with each holder 11 for projecting the cards C therefrom to assume stepped or graduated positions where their identifying means are plainly visible.

In accordance with the broader aspects of the invention the container or box 10 may be of any suitable type or construction. In the drawings I have shown a metal box 10 comprising a bottom 13, spaced sides 14, a front 15 and a back 9. The box 10 is rectangular and elongate and spaced longitudinal ribs or ridges 16 extend along the box bottom 13 and project upwardly in the box. The front 15 and back 9 are hinged at their lower edges to the bottom 13 and are adapted to be swung between a vertical position and an open or inclined position. The side walls or sides 14 of the box 10 are hollow or double and a typical lever mechanism 17 connects the box front 15 with the back 9 for a simultaneous movement whereby the manual lowering of the front 15 effects a corresponding movement of the box back.

The invention provides guides 18 in the box 10 for guiding and centering the cards C. The guides 18 are in the nature of elongate strips or members secured to the inner surfaces of the box sides 14. The inner surfaces of the box sides 14 are preferably inclined downwardly and inwardly and the guides 18 are secured to them some distance above the box bottom 13 leaving relatively narrow grooves or slots 19. The inner sides and tops of the guides 18 are preferably bevelled or rounded, as illustrated. Screws 20 or other suitable securing members may attach the guides 18 to the box sides 14. The guides 18 may be applied to typical file boxes, etc. to adapt them for the reception of the holders 11 and cards C of the invention.

The holders 11 are provided to contain the respective groups or packs of cards C in such a manner that the cards of the adjacent packs do not become mixed. It is a feature of the invention that the holders 11 are simple, inexpensive, folder-like elements. In the preferred

form of the invention the folders 11 are identical. Each holder 11 comprises a front member 21 and a back member 22. The members 21 and 22 may be identical in shape and construction to provide for economy of manufacture. The front and back members 21 and 22 of the holders 11 may be formed of cardboard, fiber board, sheet metal, or the like. The members 21 and 22 are generally rectangular and are proportioned to have their opposite ends in spaced relation to the sides 14 of the box 10. The upper corners of the members 21 and 22 are preferably rounded. Each folder 11 further includes a bottom 23 hinged to the lower edges of the front and back members 21 and 22. The bottoms 23 of the holders 11 are flat strap-like members and are adapted to rest on the ribs 16 on the bottom of the box 10. The bottoms 23 may be formed of the same material as the front and back members 21 and 22. Straps 24 of fabric, or the like, may be glued or otherwise secured to the lower edge portions of the front and back members 21 and 22 and to the surfaces of the bottoms 23 to hinge the members 21 and 22 to the bottoms. The hinge straps 24 may be provided on both the internal and external surfaces of the members 21 and 22 and the bottoms 23. The front and back members 21 and 22 and the bottoms 23 are cut away at their lower corners, as shown at 25, to have proper clearance with the guides 18. The holders 11 may be proportioned to project above the upper end of the box 10 when their bottoms 23 rest on the ribs 16. It will be apparent how a plurality of the holders 11 may be arranged in the box 10 with the back and front members 21 and 22 of adjacent holders arranged in adjacent relation or in engagement. When the box front 15 and the box back 9 are lowered the holders 11 have freedom of movement in the box 10 so that any one folder or several folders may be easily opened or manipulated.

The invention provides novel and effective means for retaining the card holders 11 in the box 10. These means comprise straps or strips 29 arranged through the holders 11 to engage downwardly against their bottoms 23. The straps 29 may be formed of cardboard, sheet metal, fiber board, or the like. The straps 29 project beyond the opposite ends of the holder bottoms 23 and their projecting end portions are received in the slots 19. The engagement of the straps 29 with the grooves or slots 19 limits or prevents upward movement of the holders 11 in the box 10. The holders may be easily inserted in the box 10 whereupon the straps 29 may be sprung upwardly between their ends to permit the entrance of their end portions in the slots 19. The straps 29 may slide or shift longitudinally in the slots 19 to permit movement of the holders 11 in the box 10. When it is desired to remove a holder 11 from the box 10 the intermediate portion of the strap 29 may be flexed upwardly or bowed to spring the end portions of the straps out of the slots 19 whereupon the holder is free for removal.

The cards C are provided to carry the entries or postings and, of course, may be employed to receive data of any character. The cards C are preferably lined or ruled and the entries or data may be written, printed, or typewritten upon them. In the preferred construction the cards C are substantially rectangular and are of substantially the same size and shape as the front and back members 21 and 22 of the holders 11. In accordance with the invention each holder 11

is adapted to receive or contain a pack of cards C. The cards C may rest on the straps 29 and their lower corners are rounded and adapted to cooperate with the guides 18 in the box 10. The engagement of the guides 18 and the lower corners of the cards C effectively centers or locates the cards between the box sides 14.

Each pack of cards C as contained in a holder 11 includes a multiplicity of sub-packs or sub-groups S. Each sub-group S of cards C contains one or more cards. In the particular form of the invention illustrated in the drawings each of the sub-groups S embodies four cards C, it being understood that the number of cards in each sub-group S may be varied. In accordance with the invention the cards C are provided with tabs or projections 30 extending from their opposite vertical or side edges. The projections 30 are integral with the cards and there is one projection 30 extending from each end of each card. The outer edges of the lateral projections 30 may be in substantially the same planes as the ends of the holder members 21 and 22 assuming that the cards C are in the holders 11 and the projections 30 may all extend upwardly to the upper edges of the cards C. The lower edges or ends of the card projections 30 constitute downwardly facing shoulders 31 engageable by the lifting means 12 as will be hereinafter described. The several cards C in a sub-group S have projections 30 which are different from those of the cards in the other sub-groups S in the pack. The shoulders 31 of the cards C of the several sub-groups S in a pack are stepped or graduated, that is, the shoulders 31 of the foremost sub-group S of a pack are stepped above the shoulders 31 of the second to the foremost sub-group S and the said shoulders 31 of the second to the foremost sub-group S are stepped above the shoulders 31 of the third to the foremost sub-group S and so on. This downward stepping or graduation of the shoulders 31 is uniform or regular.

The cards C are preferably provided with classifying or identifying tabs 32. The tabs 32 may be integral parts of the cards C and project from the upper edges of the cards. Each card C preferably has one tab 32. In accordance with the invention the cards C of each sub-group S have tabs in different positions along the upper edge of the sub-group, that is, the tabs 32 of the cards in a sub-group S are staggered or offset along the upper edge of the sub-group to all be plainly visible from the front of the sub-group. Thus in the form of the invention illustrated where there are four cards C in each sub-group S there are four fully visible tabs 32 arranged along the upper edge of the sub-group. The tabs 32 may bear indicia or identifying means of any desired character and this may be written, printed, or typewritten upon the tabs.

The means 12 for lifting the cards C in the holders 11 to make their tabs 32 plainly visible is an important feature of the invention. The means 12 is such that the user may easily and quickly move the pack of cards C in any selected holder 11 to a position where the tabs 32 of all the cards C of each sub-group S are plainly visible and the means serves to retain the cards in this extended condition indefinitely or until deliberately returned to their original positions by the user. In accordance with the invention a card lifting means 12 is associated with or provided on each holder 11 and the several means 12 are entirely independent whereby the cards C

of the different holders 11 may be selectively raised.

Each means 12 includes a lifting member or lifting element 33 shiftably connected with the back member 22 of a holder 11. The lifting elements 33 are preferably in the form of plates or cards and may be constructed of cardboard, fiber board, sheet metal, or the like. The lifting elements 33 are arranged to shift vertically with respect to the back members 22 of the holders 11 and in the preferred construction illustrated the lifting elements 33 are arranged at the inner sides or forward sides of the members 22. The lifting elements 33 are of substantially the same size and shape as the back members 22 and if desired may be identical with the members 22. The means for associating the lifting elements 33 with the back members 22 for vertical movement include clips 34 of metal or the like, secured to the opposite edge portions of the lifting elements 33. The clips 34 are preferably located adjacent the lower edges of the lifting elements 33 and are preferably provided on the forward faces of the elements. The clips 34 may be secured to the lifting elements 33 in any suitable manner, for example, they may be riveted to the elements. Each clip 34 has one or more guide hooks 35 engaging about the adjacent vertical edges of the elements 33 and the back members 22. The rear portions of the guide hooks 35 may have quite extensive shiftable cooperation with the rear surfaces of the back members 22 to normally retain the opposing surfaces of the members and the elements 33 in engagement. The guide hooks 35 serve to prevent forward and rearward separation of the elements 33 from the back members 22 and guide the elements for vertical movement on the back members. Guide clips or tabs 36 may be secured to the upper corner parts of the back members 22. The tabs 36 may be formed of metal, or the like, and may be riveted to the back members. The tabs 36 have guide fingers 37 projecting forwardly at the edges of the members 22 to have shiftable cooperation with the edges of the lifting elements 33. The fingers 37 assist in guiding the elements 33 for vertical movement and serve to prevent lateral shifting or rocking of the lifting elements. The guide fingers 37 are engageable by the guide hooks 35 to limit or stop upward movement of the lifting elements 33 relative to the back members 22.

The card raising means 12 further includes lifting fingers or hooks 38 on the lifting elements 33 for cooperating with the shoulders 31 of the cards C when the lifting elements are raised. In the preferred construction illustrated the lifting hooks 38 are integral with the above described clips 34. One hook 38 projects forwardly from each clip 34. The hooks 38 are substantially horizontal and their length is equal to or greater than the thickness of the packs of cards C in the holders 11 and is substantially equal to the width of the bottoms 23. The hooks 38 have noses or outer parts 39 projecting upwardly at their outer ends. The outer parts 39 of the hooks 38 are adapted to engage against the outer or forward faces of the card projections 30 to hold the packs of cards C in position against the lifting elements 33 and to positively separate the cards in the holders 11 from the cards that may remain supported on the hooks 38. Webs or flanges 40 may be provided on the under sides of the lifting hooks 38 to strengthen the hooks.

Identifying or classifying tabs 40 are provided

on the lifting elements 33. The tabs 40 preferably project from the upper edges of the elements 33. In accordance with the invention the tabs 40 are such that they may be employed or grasped 5 to facilitate the lifting of the elements 33. The tabs 40 are preferably formed of metal or the like, and are rigidly secured to the elements 33 by rivets or other suitable securing means. Window openings 41^a are provided in the tabs 40 and the 10 tabs 40 are adapted to contain cards 26 for bearing identifying indicia. The cards 26 provided in the tabs 40 may bear alphabetical characters or numerals, or both, to identify or classify the packs of cards C in the respective holders 15 11. The cards 26 in the tabs 40 may be protected by transparent sheets or windows 27 extending across the openings 41^a. The identifying cards are preferably removable from the tabs 40.

The tabs 40 may be grasped for the purpose 20 of raising the lifting elements 33. When a card lifting element 33 is lifted in this manner from its normal position the lifting hooks 38 successively come into lifting engagement with the card shoulders 31. The guides 18 and the back member 22 of the adjacent holder center, locate and 25 confine the cards to be properly engaged by the hooks 38. Due to the graduated or stepped relation of the shoulders 31 of adjacent sub-groups S the lifting hooks 38 first come into cooperation 30 with the shoulders 31 of the rearmost sub-group S and then successively engage the shoulders 31 of the other sub-groups until they cooperate with the shoulders 31 of the foremost sub-groups S. Thus the rearmost sub-group S of cards C is 35 lifted the greatest distance and the extent of upward movement of the sub-groups S progressively becomes less so that the tabs 32 of the adjacent sub-groups S are stepped or graduated one above the other whereby the tabs 32 of all 40 of the cards C of all of the sub-groups S are plainly visible from the front of the pack. The extent of vertical movement of the lifting element 33 is such that the upper edges or tabs 32 of all of the cards C in the holder are projected 45 above the upper edge of the box 10. Figs. 1 and 3 of the drawings illustrate one of the elements 33 in its raised position and illustrate a portion of a pack of cards in one holder 11 extended in such a manner that their tabs 32 are all plainly 50 visible.

The card lifting means 12 further include structures or means for releasably retaining the lifting elements 33 in their raised positions where the tabs 32 of the cards C in the respective holders 11 are plainly visible, as described above. In the preferred construction illustrated in the drawings a latching or retaining clip 41 is secured to the rear side of each lifting element 33. The clips 41 may be formed of metal or the like 55 and may be secured to the elements 33 by rivets. The clips 41 are of substantial length and extend transversely or horizontally, as best illustrated in Figs. 5 and 6 of the drawings. The lower edge portions of the clips 41 are shaped or bent to 60 have hook-like parts 42 for cooperating with the upper edges of the back members 22 of the holders 11 to retain the elements 33 in their raised positions. It is preferred to provide raised lips 43 on the upper edges of the back members 22 to be 65 engaged by the parts 42. The hook parts 42 are shaped to engage downwardly against the lips 43. When a lifting element 33 is raised to its up 70 position where the clips 34 or their hooks 35 engage against or are adjacent the guide fingers 37 the lifting element 33 is flexed or sprung 75

slightly to engage the hook part 42 over the lip 43 of the back member 22. The hook part 42 engaging the lip 43 is operable to retain the lifting element 33, and the cards C raised thereby, in their up or raised positions. The hook part 42 may be easily disengaged from the lip 43 by lifting upwardly on the element 33 and flexing the element to move the hook part out of engagement with the lip. When the lifting elements 33 are in their down or normal positions the hook parts 42 engage against the forward surfaces of the back members 22 of the holders. 10

It is believed that the use or operation of the filing device or card index system of the present invention will be readily understood from the foregoing detailed description. Normally, or under normal conditions, the lifting elements 33 may be in their down positions where the cards C of the several holders 11 rest upon the straps 29. When the cards C are in this condition they 20 constitute compact groups or assemblies that occupy a minimum amount of space and that may be substantially entirely received in the box 10. With the parts in their normal positions, as just described, the lifting and identifying tabs 40 25 of the elements 33 are all plainly visible at the upper side of the assembly.

When it is desired to examine, remove or refer to the cards C in one of the holders 11 the tab 40 of the lifting element 33 of that holder is 30 grasped and the element is lifted or pulled upwardly. As described above, such lifting of an element 33 brings the lifting hooks 38 into engagement with the shoulders 31 of the cards C. The shoulders 31 of adjacent sub-groups S are 35 stepped in such a manner that the hooks 38 successively come into engagement with the shoulders of the adjacent sub-groups to successively raise the sub-groups of cards. The rearmost sub-group S is raised or projected the greatest 40 distance and the extent of upward movement of the sub-group S decreases in a downward or forward progression. This raising of the several sub-groups S of cards brings the cards to the positions illustrated in Fig. 1 and in the right-hand portion of Fig. 3 where the identifying tabs 32 of the adjacent sub-groups S are stepped one above the other, to be plainly visible from the front of the assembly. Where the tabs 32 of the sub-groups S are related as described above, the 45 lifting of the element 33 brings the cards to positions where all of the tabs 32 of all of the cards in the holder are plainly visible. When the upward movement of the lifting element 33 is stopped by the engagement of the clips 34 with the guide fingers 37 the element may automatically flex slightly to engage the hook part 42 over the lip 43 of the back member 22. This 50 releasably latches the lifting element 33 in the raised position where the cards C are fanned out 55 or made visible, as described above.

It is to be understood that any one or all of the lifting elements 33 may be manipulated or raised as described above, to raise the cards C to the positions where their tabs 32 are all plainly 60 visible. The strips 29 cooperating with the slots 19 prevent unintentional or accidental upward displacement of the entire holders from the box 10. With the cards of a holder 11 held in the raised or exposed position illustrated in Figs. 1 and 2 of the 65 drawings, the cards may be individually or collectively removed from the holders. The cards C are entirely free or unattached and may be withdrawn from the holder or holders or individually or collectively swung forward to expose the data 70 75

on adjacent cards. The cards C may be individually or collectively raised over the hook parts 39 as examined or used, or for the purpose of exposing other cards, and then dropped into the holder to rest against the front member 21 which may be inclined forwardly and upwardly. The cards C thus dropped fall into positions in the proper sequence and are definitely separated from the cards remaining in the elevated positions. The identifying or classifying data on the card tabs 32 of course facilitates the restoration of the cards to their proper places. The cards C are restored by merely dropping them into the holder 11 where the guides 18 automatically center them and the hinged bottom 23 and the front member 21 confine them against falling or slipping. The lifting hooks 38 engage against the shoulders 31 of the cards to support them in their elevated positions and when a card C is restored to its pack its shoulders 31 are engaged against the hooks 38. In the event that a card C is returned to its pack out of its proper place its shoulders 31 engage the hooks 38 and support the card in a position where its upper portion and its tab 32 project above or below the tabs of the adjacent cards clearly indicating the incorrect restoration of the card.

Where the holders 11 are arranged in a box of the character illustrated in the drawings the holders may be inclined upwardly and rearwardly in such a manner that the tabs 32 of the elevated or fanned out cards C are fully exposed and plainly visible. With the holders 11 in this inclined position the cards C are centered and located by the guides 18, the hinged bottoms 29 and the front members 21 to be in position for engagement by the hooks 38 without the necessity of manually handling or straightening them. The lifting elements 33 of a plurality of holders 11 or of all of the holders may be raised to bring the cards C to their elevated positions where their tabs are fully visible. When the cards C of all of the holders 11 or of several of the holders 11 are to be examined or used they may be manipulated or removed from the foremost holder 11 and following their restoration to the holder the said foremost holder may be tipped forwardly to lie against the front 15. This procedure may be repeated with the succeeding holders 11 so that all of the cards C of the several holders may be readily and rapidly handled.

When it is desired to return the pack of cards C of a holder 11 to their original compact condition the tab 40 of the lifting element 33 is engaged to lift the element and tip or flex it for the purpose of releasing the hook part 42 from the lip 43. When this has been done the lifting element 33 may be dropped or moved downwardly to its normal position. Downward movement of the lifting element 33 is accompanied by the downward movement of the cards C and the cards assume their original positions where their upper edges lie in the same horizontal plane. If it is desired to remove a holder 11 and its cards C from the box 10 the cards are first removed from the holder and the strip 29 is then sprung out of the slots 19 wherupon the holder 11 may be bodily withdrawn from the box 10. Additional holders 11 may be easily inserted in the box and secured in place by means of the strips 29.

Having described only a typical preferred form and application of my invention, I do not wish to be limited or restricted to the specific details herein set forth, but wish to reserve to myself any variations or modifications that may appear

to those skilled in the art or fall within the scope of the following claims:

Having described my invention, I claim:

1. A unit for a card index system comprising a holder having connected front and back parts, a plurality of cards in the holder having projections at their opposite ends, the lower edges of the projections of different cards being at different elevations, an element bodily shiftable vertically on the back part of the holder, and parts on the element cooperable with said edges to elevate the cards in the holder.

2. A unit for a filing system comprising a plurality of sheets, a holder removably containing the sheets in a pack, the sheets having end parts presenting shoulders, the cards of the pack being related so that their shoulders are in a stepped series, and means bodily slideable vertically on the holder and cooperable with said shoulders to raise the sheets in the holder to stepped elevated positions.

3. A unit for a filing system comprising a pack of individual sheets, a holder for the pack including a back against which the pack may rest, laterally projecting tabs on the sheets, the sheets being arranged in the pack so that the lower edges of their tabs are in stepped series, and an element shiftable on said back and cooperable with the said edges of the tabs to lift the sheets to positions where their upper edges are in a stepped series.

4. A unit for a filing system comprising a pack of cards, laterally projecting tabs on the cards, the lower edges of the tabs being at different elevations, a holder removably holding the cards with their upper edges in substantially the same plane and with the lower edges of their tabs in stepped relation, an element shiftable vertically on the holder, and hooks on the element cooperable with the said lower edges of the tabs during upward movement of the element to elevate the cards to positions where their upper edges are in stepped relation.

5. A unit for a filing system comprising a pack of cards, laterally projecting tabs on the cards, the lower edges of the tabs being at different elevations, a holder removably holding the cards with their upper edges in substantially the same plane and with the lower edges of their tabs in stepped relation, an element shiftable vertically on the holder and cooperable with the lower edges of the tabs during its upward movement to elevate the cards to positions where they are in stepped relation, and releasable means for holding the element in the position where the cards are elevated.

6. A unit for a filing system comprising a holder including a back member, a plurality of cards removably arranged in the holder, laterally projecting tabs on the cards, the lower edges of the tabs of the cards being in stepped relation, an element shiftable vertically on the back member, parts on the element cooperable with the lower edges of the tabs during upward movement of the element to elevate the cards and freely support them in stepped relation, and a latch part on the element cooperable with the back member to hold the element and cards elevated.

7. In a filing system of the character described, a pack of sheet elements, said pack comprising sub-groups each comprising a plurality of elements, laterally projecting tabs on the elements, the lower edges of the tabs of the elements in any one sub-group being in the same plane and the lower edges of the tabs of the elements of

different sub-groups being in stepped relation, a holder for the pack, and lifting and supporting means on the holder including a manually movable member having parts cooperable with the 5 said lower edges to raise the sub-groups to assume positions in stepped relation, and releasable means for positively holding said member in the position where the sub-groups are in stepped relation.

8. A device of the character described including, a container, a plurality of holders in the container each including a front member and a back member, and means hingedly connecting the lower edges of the members, a pack of cards removably positioned in each holder, lateral projections on the cards, the lower edges of the projections of each pack being in stepped relation, a lifting element shiftable vertically on the back member of each holder, and parts on the elements cooperable with the lower edges of the projections to raise the cards so that the cards of the respective packs are in stepped relation.

9. A device of the character described including, a container, a plurality of holders in the container each including a front member and a back member, and means hingedly connecting the lower edges of the members, a pack of cards removably positioned in each holder, lateral projections on the cards, the lower edges of the projections of each pack being in stepped relation, 25 a lifting element shiftable vertically on the back member of each holder, parts on the lifting elements cooperable with the lower edges of the projections to lift the cards so that the cards of the respective packs are in stepped relation, and latches on the lifting elements engageable with the back members to hold the elements in the raised positions.

10. A device of the character described including, a container, a plurality of holders in the 40 container each including a front member and a back member, and means hingedly connecting the lower edges of the members, a pack of cards removably positioned in each holder, lateral projections on the cards, the lower edges of the projections of each pack being in stepped relation, 45 a lifting element shiftable vertically on the back member of each holder, identifying tabs on the lifting elements manually engageable to raise the elements, and parts on the elements cooperable with the lower edges of the projections to raise the cards so that the cards of the respective packs are in stepped relation.

11. A device of the character described including, a container, a plurality of holders in the container each including a front member and a back member, and means hingedly connecting the 55

lower edges of the members, a pack of cards removably positioned in each holder, lateral projections on the cards, the lower edges of the projections of each pack being in stepped relation, a lifting element shiftable vertically on the back member of each holder, means guiding the elements for substantially vertical movement on the back members, and parts on the elements cooperable with the lower edges of the projections to raise the cards so that the cards of the 10 respective packs are in stepped relation.

12. A device of the character described including, a box having a bottom and sides, guides on the sides adjacent the lines of joinder of the sides and bottom, holders in the box, packs of 15 cards in the holders located through their cooperation with the guides when in their normal positions in the holders, and means on the holders for raising the cards so located to make their upper portions plainly visible.

13. A unit for a filing system comprising a holder including a back member, a plurality of cards removably arranged in the holder, laterally projecting tabs on the cards, the lower edges of the tabs of the cards being in stepped relation, 25 an element shiftable vertically on the back member, parts on the element cooperable with the lower edges of the tabs during upward movement of the element to elevate the cards and freely support them in stepped relation, means guiding 30 the lifting element for movement on the back member and operable to limit upward movement of the element, and a clip on the lifting element cooperable with the upper edge of the back member to releasably hold the element in the raised 35 position.

14. A unit for a filing system comprising a holder including a back member, a plurality of cards removably arranged in the holder, laterally projecting tabs on the cards, the lower edges 40 of the tabs of the cards being in stepped relation, an element shiftable vertically on the back member, parts on the element cooperable with the lower edges of the tabs during upward movement of the element to elevate the cards and 45 freely support them in stepped relation, identifying tabs on the upper edges of the cards, the tabs of adjacent cards being in offset relation, means guiding the lifting element for movement on the back member and operable to limit upward 50 movement of the element, and a clip on the lifting element cooperable with the upper edge of the back member to releasably hold the element in the raised position.

HARRY A. WARDY. 55
